SANITARY COLLAPSIBLE CONTAINER

Walter A. Roselle, New York, N. Y.

Application December 3, 1935, Serial No. 52,634

6 Claims. (Cl. 221—60)

My invention relates to an improved type of collapsible container. More particularly my invention contemplates the production of a collapsible container which has all of the desirable characteristics of metal containers with regard to strength and non-resilient compressibility (deformation), while overcoming the defects of metal containers with regard to expense, and the possibility of contamination of contents.

10 An object of my invention is to provide a complete tube and nozzle structure of extraordinary strength and cheapness.

Another object of my invention is to produce a suitable collapsible container for cosmetics, food products, or like materials. The container is especially designed so that it will not contaminate or have any deleterious effect upon the contents of the tube.

Still another object is to make a tube and nozzles which combine the features of strength, cheapness, non-resilient compressibility, and inertness to the contained products.

Other objects of my invention will be apparent from the following detailed description when taken 25 in connection with the accompanying drawing in which:

Fig. 1 is an enlarged fragmentary sectional view of a completed container according to my invention.

30 Fig. 2 is an enlarged elevation of the top joint members in one stage of assembly, parts being broken away.

Fig. 3 is a partial section of the same in another stage of assembly, with parts broken away.

35 Fig. 4 is a perspective view of the elements of the container before assembly.

The container according to the preferred form of my invention includes in general a top member, an inner tube, and an outer tube. The top member 10, in the form shown, has a hood portion 11 with a depending flange 12 having a rounded edge 13. Outside of the flange 12 is a shoulder 14 formed on the bottom of the hood.

40 The top of the hood terminates in a nozzle 15 to which may be secured a closure 16 of any appropriate design.

45 The entire top member must be made of material which is impervious and not subject to chemical action with the contents of the tube. Such material must be chosen with care when unstable chemical products, cosmetics, or food-stuffs are to be contained in the tube.

50 Besides the necessary inactive chemical character of the top, the same must also be substan-

tially rigid or incompressible and hard in order to use the joining media hereinafter described.

Some substances which have these desirable properties include phenolic condensation products, resinous compositions, cellulose compounds and hard rubber.

5 The collapsible tube body includes an outer cylindrical tube 17 which, before joining with the top, is flared at one end as at 18. This tube is made preferably of thin metal foil, and, because 10 of the character of the rest of the container, the foil need not be as thick as most foils for tubes and may be made from cheaper metals. This tube may be extruded or drawn or made in any 15 suitable fashion.

A lining tube 19, with a flared end 20, is placed 20 inside of the tube 17. This liner is, like the top 10, made of a material which is chemically inert to the contents of the tube. However, this tube must be flexible in order to collapse properly when 25 in use. Materials suitable for the inner tube include hydrated cellulose, cellulose acetates, rubber base compounds and many others.

This tube may be made in any suitable fashion, 30 helically wound, wrapped with a straight seam, or otherwise, so long as precaution is used to prevent any open seams, but preferably helically wound. This tube, while it need not be particularly thick or strong because it is supported by the outer wall, must be impervious to the contents of 35 the tube.

The edges of the non-metallic strip used in 40 making the inner tube or lining are preferably united by some adhesive or some softener or solvent for the material.

A closed ring 21 is used to join the tubular members to the top. This ring is of a material 45 much harder than any of the tube materials and of limited elasticity. A superior material for the ring has been found to be steel. Other materials with the requisite characteristics might be used.

In assembling my improved container, the inner and outer cylindrical tubes are first 50 assembled, their ends being flared so that the flared inside diameter of the inner tube is just enough to slip over the flange 12. The outside diameter of the inner tube at the flare is the same as the inside diameter of the outer tube at the flare, or in other words, the inner and outer tubes fit 55 closely together at the flared portion as well as elsewhere. Note Fig. 2.

The flared tubes are next slipped over the flange 12 and the ring 21 is slid along the assembled tubes. In order to make a proper joint, 55

the inside ring diameter is almost identical with the outside diameter of the outer tube, or just sufficiently larger so that the ring can be slipped on to the tube.

5 Another dimension of importance is the outside diameter of the flange 12 in relation to the inside of the ring. As shown in Figs. 2 and 3, the outer dimension of the flange is equal to the inside dimension of the ring, no provision being made for the size of the tubes. Strictly speaking, the ring could just be slipped on to the flange without expansion if the tubes were not present.

Now when the ring, tubes and top are in the position of Fig. 3, the ring is forcibly driven over the enlarged portion of the tubes. The rounded edges 13 aid in permitting the ring to be forced on. The incompressible top prevents the tubes from collapsing, and the ring expands slightly, biting a little into the outer tube and compressing the tubes between the hard ring and the rigid flange. Because the ring is closed, every point on the circumference is subjected to stress, and the two tubes are held tightly between the flange 12 and the ring 21.

The shoulder 14 serves as a seat for the ends of the tubular pieces and as a stop for the ring. This structure adds to the neatness of appearance of the container.

30 Surprisingly enough, although the inner tube has no direct contact with the ring and although the outer tube has no direct contact with the flange, both tubes are so tightly held to the top and to each other that no adhesives or equivalent securing means between the inner and outer tubes are necessary. This eliminates an added cost item usually necessary in laminated structures.

After the parts have been assembled as above 40 described and the contents inserted, a clip 22 or other closing means is used to complete the package. Because both tubes are coincident in length, it is not necessary to have any special type of closure at this end, the contents being 45 protected from contamination by the tube 19.

In use, the outer metal tube gives the container the property of collapsibility and enables the same to be rolled up and stay rolled up as the contents are used. This outer tube also protects 50 the inner tube from exterior strains.

The inert chemical character of the inner tube and the top makes the shipment of delicate food-stuffs, cosmetics and unstable chemicals entirely safe, while permitting the use of lead foil or 55 other metals usually chemically objectionable in the outer wall structure. The cheaper metal foils are, in fact, desirable in the reduction of cost.

60 The rigidity of the top adds to the strength of the nozzle and makes the superior joint possible. Because the top is made separately from the tube, expensive coating and moulding operations are not necessary. Plain cylindrical tubes may be easily manufactured in any length and cut 65 up into the desired size. Contrast this to structures in which special machinery and methods are necessary to produce the tube and nozzle end in one piece or in which the tube wall must be specially manipulated in order to join it with a 70 separate top.

In the present invention the only change in the cylindrical tubes is the flaring of the ends. This can be done by a simple wedging or expanding tool and the rounded edge 13 on the 75

flange aids in positioning the flared portions on the nozzle top.

The complete container is of particular benefit for the sanitary and safe keeping of foods, or cosmetics, including facial creams, tooth pastes, shaving creams and other products, or any other substances which might be chemically unstable or active when brought into contact with usual collapsible tube materials. The following claims should be read with this field of use in mind. 10

I claim:

1. A collapsible container for foodstuffs, cosmetics and the like comprising an outer tube of collapsible metallic foil, an inner tube of collapsible material impervious and chemically inert to the material contained therein and coextensive with said outer tube, both of said tubes being enlarged at one end thereof, a nozzle member of substantially incompressible material impervious and chemically inert to the tube contents, said nozzle including an annular flange of a size at least as great as the outside size of the outer tube body, the enlarged portions of the inner and outer tubes both being seated upon the flange, a closed compression ring of material substantially 25 harder than the tube materials tightly surrounding said enlarged tube portions and said flange and holding the same tightly together and means for holding together and closing the other ends of said tubes. 30

2. A collapsible container for foodstuffs, cosmetics and the like comprising an outer cylindrical tube of collapsible metallic foil, an inner cylindrical tube of collapsible non-metallic material coextensive with said outer tube and impervious and chemically inert to the material contained therein, both of said tubes being of enlarged diameter at one end thereof, a top member of substantially incompressible non-metallic material impervious and chemically inert to the tube contents, said top including a cylindrical flange of an outside diameter at least as great as the outside diameter of the outer tube body, the enlarged portions of the inner and outer tubes both being seated upon the flange, and a closed compression 40 ring of material substantially harder than the tube materials tightly surrounding said enlarged tube portions and said flange and holding the same tightly together. 45

3. A collapsible container for foodstuffs, cosmetics and the like comprising an outer cylindrical tube of collapsible metallic foil, an inner cylindrical tube of collapsible non-metallic material impervious and chemically inert to the material contained therein, said tubes being mutually coextensive and closely fitting each other, both of said tubes being of enlarged diameter at one end thereof, a top member of substantially incompressible non-metallic material impervious and chemically inert to the tube contents, said top including a cylindrical flange of an outside diameter at least as great as the outside diameter of the outer tube body, the enlarged portions of the inner and outer tubes both being seated upon the flange, a closed compression ring of material 55 substantially harder than the tube materials tightly surrounding said enlarged tube portions and said flange and holding the same tightly together and closing the other ends of said tubes, said tubes being 60 free from each other throughout their lengths except at the top joint and end closure. 65

4. A container for chemically active materials comprising an outer collapsible tubular member formed of soft metal, an inner collapsible tubular 75

- member formed of soft non-metallic material substantially impervious and chemically inert to the tube contents, a separately formed neck member of substantially incompressible material impervious and chemically inert to the tube contents, and a seamless uniting ring of material harder than the tubular members, said neck member having an outer wall of larger diameter than the inside diameter of the main part of the 10 inner tubular member, said tubular members both having a mouth portion of larger diameter than the diameter of the main part, said mouth portions being seated one within the other and on the outer wall of the neck member, said ring 15 surrounding the enlarged mouths of the tubular members and being under tension and holding the tubular members tightly on the neck member.
5. A sanitary container comprising an outer cylindrical tube of non-resilient collapsible material, an inner cylindrical tube of collapsible material coextensive with said outer tube and impervious and chemically inert to the material contained in the tube, both of said tubes being 20 of enlarged diameter at one end thereof, a top member of substantially incompressible material impervious and chemically inert to the tube contents, said top including a cylindrical flange of an outside diameter at least as great as the outside 25
- diameter of the outer tube body, the enlarged portions of the inner and outer tubes both being seated upon the flange, and a closed compression ring of material substantially harder than the tube materials tightly surrounding said enlarged 5 tube portions and said flange and holding the same tightly together.
6. A sanitary container comprising an outer collapsible tubular member formed of soft material, an inner collapsible tubular member 10 formed of soft material substantially impervious and chemically inert to the tube contents, a separately formed neck member of substantially incompressible material impervious and chemically inert to the tube contents, and a seamless uniting 15 ring of material harder than the tubular members, said neck member having an outer wall of larger diameter than the inside diameter of the main part of the inner tubular member, said tubular members both having a mouth portion 20 of larger diameter than the diameter of the main part, said mouth portions being seated one within the other and on the outer wall of the neck member, said ring surrounding the enlarged mouths of the tubular members and being under 25 tension and holding the tubular members tightly on the neck member.

WALTER A. ROSELLE.
